TOY AIRPLANE

William Kramer, Richmond Hill, N. Y., assignor
to Ideal Aeroplane & Supply Co., Inc., New
York, N. Y., a corporation of New York

Application July 3, 1935, Serial No. 29,595

1 Claim. (Cl. 46—76)

This invention relates to toy or model airplanes and my improvements are directed to means for the simple and economical construction and assembly of the parts thereof.

5 Essentially my invention consists in forming the fuselage of such toy airplane from a single sheet of buckram or other suitable stiff, mouldable material, whose opposite edges are cemented together to constitute a closed hollow body, of 10 light weight and having sufficient strength to withstand the usage to which the toy airplane is put.

Also the fuselage, as formed, includes a vertical stabilizer by suitably shaping opposite rear 15 portions of the sheet, bringing said portions into ply relation and cementing them together, the doubled thickness giving increased rigidity to this vertical stabilizer.

Also the moulded fuselage is provided with 20 respective means for carrying the supporting airfoil and the horizontal stabilizer.

Further the moulded fuselage is equipped at 25 its nose with a removable bearing cap for the propeller shaft, and said fuselage, at its rear under surface has localizing means for engaging 30 the terminal hook of the power band.

Still further the moulded fuselage at its forward under surface, is provided with a fitting for the releasable engagement of a bent wire 35 which carries the landing wheels.

Other features of my invention will hereinafter appear.

In the drawings:

Figure 1 is a plan view, partly broken away, 35 of my improved toy airplane.

Fig. 2 is a side sectional view thereof.

Fig. 3 is a partial detail perspective view, showing the means for removably connecting the landing gear.

40 Fig. 4 is a section on the line 4—4 of Fig. 2.

Fig. 5 is a section on the line 5—5 of Fig. 2.

Fig. 6 is a perspective elevation of the toy airplane having modified means for detachably connecting thereto the wing and horizontal stabilizer, 45 and

Fig. 7 is a side view, partly in section, of Fig. 6.

In Figs. 1 to 5, illustrating my invention in one form thereof, let 1 indicate the fuselage, 2 the supporting airfoil, 3 the horizontal stabilizer, 4 the vertical stabilizer, 5 the propeller, having 50 shaft 6 and power band 7, 8 the shaft bearing member, and 9 the landing gear.

One feature of my invention consists in the formation of the fuselage from a single sheet of 55 stiff, mouldable material, such for example as

buckram, which material is cut to the desired configuration and then moulded into the hollow, fuselage contour indicated in the drawings, with its opposed edges 10 cemented together to complete the formation.

At the rear of the hollow fuselage structure the opposite end portions of the sheet material which are preformed as indicated, are brought together, in ply form, and united by cement to thus constitute the vertical stabilizer 4.

10 In the moulding of the fuselage reinforce ribs 11, 12, are formed, extending respectively longitudinally and transversely, these ribs stiffening the hollow structure and aiding to maintain its contour against deformation.

15 The nose of the fuselage is provided with a metallic annulus 13 which is adapted for the reception of a removable plug or button constituting the bearing member 8 that has an axial orifice to receive the propeller shaft 6. Said 20 shaft 6, which carries propeller 5, has a terminal hook 14 that engages the power band 7.

The other end of the power band is engaged by a hook 15 which itself is engaged in an eyelet 16 that is secured in the under surface of the 25 fuselage, at the rear thereof.

The landing gear 9 consists of a bent wire whose respective ends carry the wheels and whose doubled centre is angled and adapted to fit slidably in a socket 17 formed on a plate 18 which 30 has lugs 19 that are clamped to the fuselage at its forward under surface.

The supporting airfoil, or wing 2 is removably connected to the fuselage in the example of Figs. 1 to 5, by passing it through aligned slots 20 35 formed in the opposite sides of the fuselage and centering it therein, the depth of said slots being such that the wing will be frictionally held therein.

Also, toward the rear of the fuselage other slots 40 21 are provided for the like reception of the horizontal stabilizer 3.

In the modified form of my invention illustrated in Figs. 6 and 7, all the structural parts of the toy airplane are identical with those of Figs. 1 to 5, excepting only that the modes of connecting the wing and horizontal stabilizer differ. Thus, in Figs. 6 and 7 the under surface of the fuselage is provided with jogs or steps 22, 50 23. The wing 2 is fitted against the fuselage bottom behind step 22, and the stabilizer 3 is fitted against the fuselage bottom behind step 23. In order to localize the wing and stabilizer respective rubber bands 24, 25 are placed about 55

the fuselage and said elements in the usual manner common in this art.

Also, in these views the vertical stabilizer 4 is shown as provided with moulded reinforce ribs 5 26.

Variations within the spirit and scope of my invention are equally comprehended by the foregoing disclosure.

I claim:—

10 In a toy airplane, a fuselage composed of rela-

tively stiff sheet material shaped and moulded in hollow form and having its meeting edges presenting flanges and secured together, the flanges at the upper rear portion of said fuselage being extended and shaped to form a vertical stabilizer 5 of double thickness with walls in immediate contact to afford increased rigidity, the flanges and stabilizer being in the same plane.

WILLIAM KRAMER. 10
